PIE CUTTING GAUGE AND GUIDE

John B. Tweeten, Santa Rosa, Calif.

Application April 8, 1949, Serial No. 86,295

1 Claim. (Cl. 33—1)

1

My present invention relates to gauges and guide apparatus in which a mechanical device is made use of for the purpose of accurately dividing a circular item such as a pie or a cake into an equal number of pieces.

The principal object of my invention is to provide an improved gauge and cutting guide for use in cutting pies and cakes and the like.

Another object is to provide a gauge and cutting guide for cup-shaped pastry in which the said pastry may be equally divided into accurate semi-divided portions, and

Other objects incorporated in said invention involved in the construction and operation of the device will be apparent as the description of the same develops.

Referring more in particular in the drawings,

Fig. 1 is a plan view of the device as applied to a pie or a cake to be divided into a certain number of pieces. In this particular view the device is set to cut a cake into eight equal pie-shaped pieces, the irregular outer line and top irregular lines indicate the outer edges of a cake. The dot-and-dash lines indicate the outline of the eight equal pieces into which the cake will be cut;

Fig. 2 is a cross-section taken on the line 2—2 of Fig. 1 portions of the device being shown in elevations and other portions of the cake and bottom of a cake tin being shown in fragmentary dot-and-dash lines to better illustrate the position of the device when in operation;

Fig. 3 is a fragmentary cross-section taken through the hinge portion of the device being indicated at 3—3 on Fig. 2;

Fig. 4 is a fragmentary cross-section taken on the line 4—4 of Fig. 2, and

Fig. 5 is a fragmentary plan portion of the top horizontal cutting plate showing the curved point engaged by the vertical hinge pin.

Referring to the drawings more in detail, 10 indicates a pie or a cake. 11 indicates vertical separator plate. The plate 11 is provided on one edge with an open hinge portion 12 and on another edge with an elevated key portion 13. A horizontal cutting guide plate is provided with knob member 15 secured to the plate 11 by means of a cap screw 16. Clamped to the top surface of the cutting guide plate 14 between the bottom surface of the knob 15 is a heavy wire hinge pin member one end of which is provided with a loop 16 and the other end of which is bent at ninety degrees to form a hinge pin portion 17 which fits in the open hinge portion 12 of the separator plate 11. The hinge pin, knob 55

2

and plate 14 are demountable for sanitary reasons. To make these demountable pieces easily assembled and adhere to their proper positions when assembled, I have formed a curved surface 18 in the plate 14 into which the bent over hinge pin portion 17 of the wire engages when assembled.

Of course it is apparent that other forms of hinges may be employed between the plates 11 and 14 and other means substituted for the knob 15 and be the patentable equivalent of the specific structure shown and described in present application.

In the plate 14 I have located a plurality of slotted openings 20. These slots 20 are calibrated in degrees from a zero point represented by the edge 21 of the horizontal plate 14. As noted on the drawing there are eight slots marked 24, 16, 12, 8, 7, 6, 5, 4. Any one of these 20 slots may be engaged by the key portion 13 of the separator plate 11 and in such a slot the cake or pie may be equally divided in the exact number of portions indicated by the numeral adjacent such slot.

25 In operation, if it be assumed that the cake or pie is to be cut into eight equal pieces, the apparatus will be assembled with the key member 13 located in the slot marked eight, as shown in Fig. 1. A single incision is made in the cake or pie from the center to the outer edge indicated at 25. The separator plate 11 is now inserted in the incision 25 as shown in Figs. 1 and 2. A second incision is now made in the pie or cake using the right-hand edge 21 30 of the horizontal plate as a knife blade guiding edge. The separating plate 11 is now moved into the second incision and another cut is made along the knife blade guiding edge 21. In similar manner the apparatus is progressively 35 moved in a counterclockwise direction around the pastry and all the pie-shaped pieces are of equal size.

40 It will be apparent that the device is not limited to the particular number of cutting divisions set forth in the application but the locating slots may be laid out or calibrated into various divisions, those shown in the drawings being illustrative only. It is also to be understood that I may vary the shape and proportions of the various parts of the device and substitute equivalent portions within wide latitude while still remaining within the spirit of the appended claim.

45 Having thus described my invention, what I claim as new is:

A pie segment cutting gauge comprising a

vertical plate adapted to be inserted in a radially disposed incision in said pie in combination with a segmental shaped plate pivoted at its apex to one edge and at one end of said vertical plate, stop means located on the top edge of said vertical plate engaging with stop means located in said segmental shaped plate, said vertical plate being radially movable under said segmental shaped plate to any angular position within the included angle of said segmental shaped plate.

JOHN B. TWEETEN.
